UNITED STATES PATENT OFFICE.

CHARLES J. NELSON, OF LAURUM, MICHIGAN.

POCKET MATCH-SAFE.

No. 901,548.

Specification of Letters Patent. Patented Oct. 20, 1908.

Application filed January 31, 1908. Serial No. 413,660.

To all whom it may concern:

Be it known that I, CHARLES J. NELSON, a citizen of the United States, residing at Laurium, in the county of Houghton, State of Michigan, have invented certain new and useful Improvements in Pocket Match-Safes; and I do hereby declare the following to be a full, clear, and exact description of the invention, such as will enable others skilled in the art to which it appertains to make and use the same.

This invention relates to a new and useful improvement in pocket match safes.

The object of my invention is to provide a neat, simply constructed match receiving receptacle, so arranged that after having been charged, the receptacle can be emptied of its matches, one at a time, as will be described more fully hereinafter.

In the accompanying drawings Figure 1 shows an elevation of a match-box embodying my invention. Fig. 2 is a sectional view thereof. Fig. 3 shows a bottom view. Fig. 4 is a transverse sectional view. Fig. 5 discloses an end view. Fig. 6 is a sectional view looking downward, and Fig. 7 a detail of the plunger.

In carrying out the object of my invention, I construct a match-safe, preferably of sheet metal, and marked *a* in the drawings, which is provided along one side with a longitudinal corrugation *b*, forming a match receiving channel, which extends the full length of the receptacle *a*. This receptacle at one or more points is provided with the abrading surfaces *x*, as shown, and midway of its ends, has the bottom *c'* provided with the central bead *e*, forming a channel to receive the ends of the matches, this channel emptying into and coinciding with the channel forming corrugation *b*, as disclosed.

At one end I provide the top *a'* held by the hinge *d* and at the other end the fixed cap *c* secured by solder or other means. The cap *c* is positioned below the slanting bottom *c'* and forms with said bottom a receptacle *v*.

The cap *c* is provided with suitable slots *l* and *m*, within which are held the wings of the plunger, as used in my invention. This cap is further provided with the opening *x* through which the match drops when escaping from the box *a*.

The plunger at one end has the lip *q* forming a finger piece by means of which the plunger is actuated while at the other end, this plunger is provided with the wings *n*, *n* 55 and the gate *i*, the latter being normally held within the corrugation *b*, to prevent any match within said corrugation passing out of the feed end of said channel forming corrugation. The wings *n* check the movement 60 of the plunger, as they work within the slots *l* and *m*.

In using the safe, the operator fills the magazine forming receptacle with suitable matches. Now when a match is desired, the operator so tilts the receptacle that one match will find lodgment within the channel forming corrugation *b*, then shoves the plunger *h* to uncover the feed opening at the bottom of the channel *b*. In this position, 70 one match will drop out of the channel. After the match is delivered the gate is carried into its original position to close the channel.

The device is neat and simple of operation 75 and having thus described my said invention, what I claim is—

In a match-box, the combination with a receptacle having a longitudinal corrugation forming a match-receiving channel, a bottom 80 within said receptacle having a centrally disposed bead forming a channel, said bottom slanting towards said corrugation, a hinged top secured to said receptacle, a cap secured to said receptacle below said slanting bottom, 85 said cap being slotted and having a perforation registering with said longitudinal corrugation, a plunger having extending wings held within said slots, said plunger having a finger-piece at one end working against said wings, and a gate normally resting within said channel forming corrugation, said wings limiting the movement of said plunger, as set forth.

In testimony whereof, I affix my signature, 95 in presence of two witnesses.

CHARLES J. NELSON.

Witnesses:

GUST. A. CARLSON,
THUDE GOURD.
